UNITED STATES PATENT OFFICE.

WILLIAM H. SPILLMAN AND ADOLPHUS E. ROACH, OF LEAMINGTON, CANADA.

WHIFFLETREE.

SPECIFICATION forming part of Letters Patent No. 680,006, dated August 6, 1901.

Application filed November 9, 1900. Serial No. 35,948. (No model.)

To all whom it may concern:

Be it known that we, WILLIAM H. SPILLMAN and ADOLPHUS E. ROACH, subjects of the Queen of Great Britain, residing at Leamington, in the Province of Ontario, Canada, have invented a certain new and useful Improvement in Whiffletrees; and we declare the following to be a full, clear, and exact description of the same, such as will enable others skilled in the art to which it pertains to make and use the same, reference being had to the accompanying drawings, which form a part of this specification.

This invention relates to whiffletrees, doubletrees, and neck-yokes and similar articles used for draft purposes, and has for its object an improved construction of a tubular whiffletree, doubletree, neck-yoke, or similar article made from stamped sheet metal, so bent and folded as to produce an article strong, durable, and light.

In the drawings, Figure 1 is a perspective of the whiffletree. Fig. 2 is a cross-section at the middle point of the whiffletree at the line $x x$ of Fig. 1. Fig. 3 is a cross-section at the end. Fig. 4 is a perspective showing the middle hoop. Fig. 5 is a longitudinal section through the middle hoop.

The article, whiffletree, doubletree, or neck-yoke is made in two parts, which are held together by a middle hoop and by end hoops. The part A is made from sheet metal stamped to a concave form, with the edges $a b$ turned in, so that the half A of the completed article has the shape indicated, the middle part being in cross-section about a half-circle or a half-oval, with inturned flanges, and the ends being in cross-section half-circles, with an in-turned flange from each side. The half part B is of the same shape and construction; but in assembling the two they are placed together to cause the complete structure to assume the shape of a tube having an enlarged middle part somewhat flattened, and preferably having what may be termed the "front" side or side opposite the draft attachment substantially straight, while the side that is toward the draft broadens out toward the middle of the article.

Around the middle of the article is placed a split hoop C, having bolt-lugs arranged one

on each side of the split. The ring C is concaved from end to end, so that the middle part of the ring has a somewhat larger diameter than the end parts, and the end parts of the ring are of a size to engage closely around the body of the whiffletree when the lugs c and c' are brought together and secured together by bolts or rivets through the holes d . The split concaved hoop holds the parts A and B firmly together and is itself prevented from slipping endwise by the contracted ends, which engage around the whiffletree at each side of its bulged middle part.

At each end of the article is placed a conical draft ring or hoop of a size to engage snugly around the ends of the two parts A and B, and the end edges of the parts A and B are upset or riveted over the outer end of the ring e and hold the ring from escaping endwise from the article. The rings e and e' are furnished with draft-hooks or tug-hooks, and the article is arranged to be held at its middle point by a bolt passing through the hole f or, in case it is used for a neck-yoke, by a ring passing through the hole f , or the hole f may itself be made large enough to serve as the ring.

The two halves of the article may be soldered or brazed together along the seams g ; but this is not essential to its construction, as the hoops or rings around the middle part and around the ends hold the parts securely in place.

What we claim is—

1. A new article of commerce, consisting of sheet-metal sections stamped to a concave form having inturned flanges and bound together by hoops, substantially as described.
2. An article for draft purposes consisting of sheet-metal sections stamped to a concave form and each section being provided with inturned flanges, binding-hoops provided with draft appliances securing the sections together, substantially as described.

In testimony whereof we sign this specification in the presence of two witnesses.

WILLIAM H. SPILLMAN.
ADOLPHUS E. ROACH.
